H. E. Dunlap
ATTORNEY

UNITED STATES PATENT OFFICE

JOHN H. MCCLURE, OF WHEELING, WEST VIRGINIA

AMALGAM SHAKER

Application filed February 25, 1929. Serial No. 342,526.

This invention relates to amalgam mixers, and the primary object of the invention is to provide improved means for enabling the amalgam to be easily and quickly mixed.

5 A further object of the invention is to provide a mixer of the character mentioned which is of simple and economical construction and which provides means wherein the amalgam container may be easily and quickly 10 applied to and removed therefrom.

A further object of the invention is to provide a device of this type which is composed of a minimum of parts that are compactly related.

15 In describing the invention in detail, reference is herein had to the accompanying drawings, in which—

Figure 1 is a side elevation of my invention; and—

20 Figure 2 is a side edge elevation of the same.

Referring to said drawings, the reference numeral 1 indicates a body of sleeve form having a short shaft 2 provided interiorly 25 thereof, said shaft 2 having its inner end formed with a tongue 3. The sleeve or body 1 is designed to conformably fit over the usual driving chuck of a dental engine, said tongue 3 being formed to engage said chuck 30 in such manner that it is driven by the latter.

The outer end of said sleeve 1 is formed with a bearing-like head 4 in which the shaft 2 is journaled. Located integrally on said head are diametrically opposed and outward-35 ly directed lugs 5, each of said lugs having therein a vertical slot or recess 5' in which is pivotally connected the lower ends of arms 6 and 7 therebetween, said arms being pivoted to said lugs 5 by means of pivot pins 14. The 40 outer ends of said arms 6 and 7 are provided with confronting sockets 8, the latter being designed to receive therein the ends of a capsule-like container 9.

In order to clamp the arms 6 and to hold 45 same in engagement with the container 9, a latch member 10 is provided, said latch being disposed transversely to the arms 6 and 7 and being pivoted to the arm 6. The latch- 50 ing member is formed with a bayonet slot 11 which is adapted to receive therein a pin

12 carried by the arm 7. The outer end of the stub shaft 2 has an eccentric member or disk 13 rigidly attached thereto, said disk being disposed between the inner lower sides of the arms 6 and 7, the latter preferably 55 having cut-out portions 15 in which said disk is received.

In the operation, the latching member 10 is disengaged from the pin 12 and the arms 6 and 7 separated to receive the ends of the 60 container 9 in the sockets 8 of said arms, whereupon said member 10 is moved to latched position, as shown in Fig. 1, thereby causing the container 9 to be firmly clamped by and between the arms at the socketed ends 65 thereof. Upon the sleeve 1 being applied to the driving chuck of the dental engine and the tongue 3 of the shaft or spindle 2 engaged with said chuck, it will be apparent that the eccentric disk 13 will be rotated upon the 70 starting of the dental engine, thus imparting a very rapid oscillatory movement to the container 9, causing the contents to be thoroughly mixed by the shaking movement.

It will be noted that the container may 75 be easily and quickly applied to and removed from the arms, due to its location at the outer ends of the arm, and that the latch may be conveniently manipulated to move the same into and out of engagement with the 80 container.

What is claimed is—

1. An amalgam mixer including a sleeve having a head, a shaft journaled in the head, said sleeve being formed to telescope the driving chuck of a dental engine and said shaft being formed to engage the chuck so as to be rotated thereby, a collar rigidly mounted on said head and having diametrically opposed lugs thereon, a pair of arms pivoted at their inner ends to and between the lugs, confronting sockets on the outer ends of the arms formed to engage the ends of a container, an eccentric disk carried by the shaft and formed to engage the inner ends of the arms, a latch member extending transversely of the arms and pivoted to one thereof, and means on the other arm to releasably engage the latch member whereby to clamp the container between the sockets of the arms. 100

2. An amalgam mixer including a sleeve having a head, a shaft journaled in the head, said sleeve being formed to telescope the driving chuck of a dental engine and said shaft being formed to engage the chuck so as to be rotated thereby, a collar rigidly mounted on said head, a pair of arms pivoted at their inner ends to the collar, confronting sockets on the outer ends of the arms formed to engage the ends of a container, an eccentric disk carried by the shaft and formed to engage the arms, a latch member connected to one of the arms, and means on the other arm to releasably engage the latch member whereby to clamp the container between the sockets of the arms.

3. In an amalgam mixer, a body, a pair of arms pivoted to one end of the body, means carried by the arms to engage and hold a container therebetween, a rotatable eccentric disk carried by the body and disposed between and engaging the arms to oscillate the latter, and means to latch said arms together.

4. In an amalgam mixer, a body, a container, a pair of spaced arms pivoted to the body, means to hold the container between the arms, means operating in the space between and engaging the arms to oscillate same, and means for holding said arms together.

In testimony whereof, I affix my signature.
JOHN H. McCLURE.
